UNITED STATES PATENT OFFICE.

CHESTER THOMAS MCGILL, OF ELGIN, ILLINOIS, ASSIGNOR TO REITER CO., OF ELGIN, ILLINOIS, A CORPORATION OF ILLINOIS.

GRAVITY SYSTEM FOR CONTINUOUSLY TREATING BOILER WATER.

Application filed April 8, 1926. Serial No. 21,157.

The prime object of this invention is to provide means consisting of a method and apparatus for treating boiler water, to be preferably called the Elgin gravity system, for continuously treating boiler water, for softening and purifying purposes while the boiler is in operation.

Another object of this invention is to provide suitable apparatus or means for admitting chemical treatment to the boiler water, the required treatment having been determined by some suitable test, such as the Elgin method of testing and treating boiler water in order to ascertain the kind and quantity of treatment required. Obviously, however, the apparatus herewith invented for supplying required chemical treatment to the boiler water is not confined in use to any one method for determining the required treatment.

In the drawing, the single figure illustrates a view in elevation of treatment tanks, mixing tank, steam pump and fittings in typical assembled relation to a boiler.

In a typical arrangement, numeral 1 designates the steam line to the mixing tank, and 2 the water line, while 3 leads to the suction pump 7. The siphon 4 extends into the mixing tank 5, and hinged lid 6 is a cover on the mixing tank 5. The numeral 9 represents the discharge from the steam pump to pressure treatment tanks D or E. Numerals 10 and 11 designate the valves to the gravity pressure tanks E and D, while the valve 12 leads from the gravity tank D to the treatment regulating needle point valve D', and 13 represents the valve leading from the gravity tank E to the regulating needle point valve E'.

The numeral 14 designates the valve connecting the steam boiler pressure with tank D, and 15 the valve connecting steam boiler pressure with tank E, while 16 represents the check valves to prevent flow of treatment from D or E into the steam line. Numeral 17 designates the chain wheels to operate valves 14 and 15 to steam supply from the floor, while 18 is the steam line leading to the steam pressure supply, and numerals 19 to 25, inclusive, represent the treatment lines leading to the different boilers. Numerals 32 and 33 in the drawings designate diagrammatic views of boilers adapted to be opera-

tively connected to the treatment lines 24 and 25, it being understood that individual boilers may be connected to the lines 19 and 23 in a similar manner. As a matter of fact any number of treatment lines or boilers may be attached to this system without affecting the merits of this invention. Obviously, the D' needle point valves will supply D treatment to any boiler while in operation, and in any quantity desired, while E' needle point valves are adapted to supply E treatment to any boiler in any desired quantity. The numeral 26 represents a pressure gauge, and 27 a relief valve, while 28 and 29 designate a globe stop valve, and an air pet cock. The pipe leading to the mixing tank is designated by the numeral 30, and 31 is a sieve.

When valves 14 and 15 are closed, also valves 11, 12 and 13. Chemicals are then deposited in mixing tank 5 through cover 6, and water is introduced into the tank through valve 2, to a point extending well over the mixing siphon 4. The water valve 2 is then closed, and steam valve 1 opened thereby, admitting steam into the tank which thoroughly agitates, dissolves and mixes the chemicals with the water. The valve 1 is then closed and 2 opened, filling the tank to any desired point, after which valves 3, 9 and 10 may be opened, and the liquid chemical treatment pumped by means of pump 7 from tank 5, through these open valves into tank E, when the mixing tank 5 is empty valve 10 may be closed.

The chemicals for D treatment are then put in the mixing tank 5 as before, and when thoroughly mixed, valve 11 must be opened so that the liquid may be pumped to tank D.

When the mixing tank is again empty tank D should be full, then valve 11 must be closed, and the tanks D and E now being filled with chemicalized liquid treatment the system is ready for admitting the treatment from the different tanks to the boiler water in estimated proportion for softening the water to the desired point. This proportion may be obtained by different methods, preferably by the applicant's co-pending application, on a means and process for treating boiler water in order to ascertain the kind and quantity of treatment required. In order to admit treatment from the different gravity tanks to

the boiler, valves 13, 14 and 15 are opened, admitting treatment flow through the line to all valves marked E', for example, to treat water in boiler 25, the needle valve E' is opened 5 from one quarter to one half turn. The liquid will then flow by gravity through valve E' and pipe 25 to the boiler, just in proportion to the opening of the valve.

If the test of the boiler water shows that 10 more D treatment is required, then valve 12 is opened letting the liquid flow in the line from D tank under all the valves marked D', then open the D' valve on line 25 one quarter to one half turn, letting some D treatment 15 flow through pipe 25 to boiler. The D' and E' valves on line 25 now both being opened a small amount, the treatment can be adjusted through the D' and E' valve to get any desired strength on the D and E test. The D' 20 and E' valves may be entirely closed if necessary, should either treatment be too strong. This same operation will apply on the D' and E' valves to any line, as for instance, 19 to 25, inclusive, leading to boilers, and the water 25 can be treated continuously to any degree of hardness.

To refill D tank close chain valve 14 and valve 12, also valve 9, then open valve 11, 28 and air cock 29. This will let tank D relieve 30 its pressure with any condensed water therein through the mixing tank 5, after which more chemicals are placed in the tank and mixed as before. In refilling either D or E tank valves 14 and 15 in steam supply line 35 should be closed, also valves 12 and 13. Either one of these tanks may be filled while the other is in operation. The manner of administering the treatment through pipe line 25 will apply to any one of the other branch 40 lines to different boilers.

This invention provides means for feeding chemicalized liquid to the boiler, independent of the feed water lines, thereby eliminating, 45 when treating water largely of temporary hardness, of the scaling up of the feed water lines when treating water containing largely, temporary hardness due to the chemicalized treatment, and the heated water from the hot water heater causing a quick separation of 50 the solids which lead to the feed water line. It has been found that discontinuing the treatment into the feed water lines and supplying treatment direct to the boilers, that it 55 eliminates the scaling up of feed water lines.

55 What I claim is:

1. A gravity pressure system for continuously treating boiler water while the boiler is in operation, consisting of gravity pressure tanks containing chemicalized liquid treatment, and means for admitting treatment of any desired chemical combination from the tanks to the boiler, consisting of controls for regulating the amount of liquid from each tank, thereby adapted to adjustment for the required degree of hardness in the boiler

water, and means for admitting required percentage of chemicalized liquid from gravity pressure tank.

2. A gravity pressure system for continuously treating boiler water while the boiler 70 is in operation, consisting of gravity pressure tanks containing chemicalized liquid treatment, and means for admitting treatment of any desired chemical combination from the tanks to the boiler, consisting of controls for regulating the amount of liquid from each tank, thereby adapted to adjustment for the required degree of hardness in the boiler water, and means for admitting required percentage of chemicalized liquid 75 from gravity pressure tank, consisting of control valves on lines leading from the pressure tanks thereby suitably conditioning and chemically balancing the boiler water.

3. A system for treating boiler water comprising a mixing tank for mixing treatment liquid, separate tanks for receiving treatment from the mixing tank, pipes connecting the mixing tank with receiving tank, and the necessary pipes and valves for connecting each 90 of the treatment receiving tanks with the boiler so that treatment in any desired proportion may be fed into the boiler for continuously treating the boiler water while the 95 boiler is in operation.

4. A gravity pressure system for continuously treating boiler water while the boiler is in operation, comprising a mixing tank for mixing the treatment liquid, separate tanks for receiving treatment from the mixing tank, 100 pipes connecting the mixing tank with receiving tank, and the necessary pipes and valves for connecting each of the treatment receiving tanks with the boiler so that treatment in any desired proportion may be fed 105 into the boiler, and means for adjusting the flow of treatment to the boiler from the treatment tanks in order to obtain and maintain a desired degree of hardness.

5. A gravity pressure system for continuously treating boiler water while the boiler is in operation, comprising a mixing tank for mixing the treatment liquid, means for allowing the flow of treatment liquid to the boiler, separate tanks for receiving treatment 110 from the mixing tank, pipes connecting the mixing tank with the receiving tank, and the necessary pipes and valves for connecting each of the treatment receiving tanks with the boiler so that treatment in any desired proportion may be fed into the boiler, and means for adjusting the flow of treatment liquid to the boiler from the treatment tanks in order to obtain and maintain a desired degree of hardness, the pressure treatment 115 tanks being adapted to hold chemicalized liquid treatment and to function by gravity.

6. A gravity pressure system for continuously treating boiler water while the boiler is in operation, consisting of gravity pres- 120

sure tanks containing chemicalized liquid treatment, means for supplying steam within the pressure gravity tanks, a mixing tank, separate tanks for receiving treatment from the mixing tank, pipes connecting the mixing tank with the receiving tank, and the necessary pipes and valves for connecting each of the treatment receiving tanks with the boiler

so that treatment in any desired proportion may be fed into the boiler, means for allowing the flow of treatment liquid to the boiler, and means for refilling the different tanks while the other tanks are in operation.

In testimony whereof I affix my signature.

CHESTER THOMAS McGILL.
